CLAIM

The ornamental design for an LED television, as shown and described.

DESCRIPTION

FIG. 1 is a top, front and right side perspective view of an LED television showing our new design; FIG. 2 is a top, rear and right side perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof;

FIG. 9 is an enlarged view of portion 9 in FIG. 1; FIG. 10 is an enlarged view of portion 10 in FIG. 1; and, FIG. 11 is an enlarged view of portion 11 in FIG. 2.

The broken lines in the drawings illustrate portions of the LED television which form no part of the claimed design. The dash-dot-dash broken lines indicate where the enlargements have been taken, and form no part of the claimed design.

1 Claim, 11 Drawing Sheets
